Ellorenz

UNITED STATES PATENT OFFICE.

OSCAR STROMBORG, OF LOS ANGELES, CALIFORNIA.

DEVICE FOR PROTECTING STRUCTURES AGAINST EARTHQUAKE DAMAGE.

Application filed January 31, 1924. Serial No. 689,824.

To all whom it may concern:

Be it known that I, OSCAR STROMBORG, a citizen of the United States, residing at Los Angeles, in the county of Los Angeles and 5 State of California, have invented new and useful Improvements in Devices for Protecting Structures Against Earthquake Damage, of which the following is a specification.

10 My invention relates to building construction and the general object thereof is to provide an improved safety mounting particularly applicable to small dwellings, by means of which the building will be protected 15 against damage from earthquakes.

Other objects and advantages will appear. Referring to the annexed drawing which forms a part of this specification—

Figure 1 is a vertical section of my safety 20 mounting in normal position.

Figure 2 is a vertical section of my mounting taken on the line 2—2 of Figure 1.

Figure 3 is a vertical section of my mounting corresponding to Figure 1, but showing 25 the building as having been moved on my mounting by an earthquake.

Figure 4 is a sectional view of my mounting corresponding to Figure 2, but showing the building as having been moved on my 30 mounting by an earthquake.

Figure 5 is a view corresponding to Figure 2 showing the building and my mounting as having been jacked up and moved back to normal position after it has been 35 moved to one side by an earthquake.

Figure 6 is a perspective view of the base member of my mounting.

My invention comprises three members, 40 namely, a base plate member 1, a base socket member 2, and a supporting member 3. The plate member 1 is embedded in the building foundation 4 with its upper surface 5 flush with the upper surface of said foundation. Said plate member is square and is provided 45 with an aperture 6 therein. The socket member is square but of less area than plate 1 and comprises a bottom wall 7 and side walls 8 upstanding from said bottom wall. Said bottom wall is provided with an aperture 9 and two opposite side walls are provided 50 with openings 10—10. The supporting member 3 is square and includes a top wall 11 and side walls 12 extending downwardly most of their length from said top wall but 55 extending a short distance above said top wall, as indicated at 13. A pair of knives

14—14 extend transversely within the supporting member 3, being joined at their upper ends to the top wall 11, and at their ends to opposite side walls 12—12. The lower 60 ends of said knives are beveled to edges 15—15. The supporting member 3 telescopes within the socket base member 2. Bars 16—16 of lead or other suitable composition are introduced edgewise through one 65 of the openings 10 into the socket member 2, upon the upper edges 17—17 of which bars the knives 14—14 rest, said knives extending across said upper edges and the knife edges 15—15 engaging said upper bar edges 70 17—17. The lower building sill 18 rests upon the top wall 11 of the supporting member 3 with the upper ends 13—13 of opposite walls 12—12 engaging the sides of said sill, and the upper ends of said other side walls 75 fitting within transverse grooves 19—19 cut in the under side of said sill, thus tying the sill to said supporting member so that it cannot move either longitudinally or transversely with relation thereto.

The sill 18 is positioned on the supporting member 3 in such position that the knives 14—14 extend transversely thereof and the bars 16 extend parallel thereto. The weight 80 of the part of the building resting upon the knives 14—14 is just enough to sink the edges thereof into the upper edges of the bars 16—16, but not enough to shear the same.

The socket member 2 is pinned to the 90 plate 1 by a pin 20 which extends through the apertures 9 and 6 in the bottom of said member and in said plate respectively.

If there is some disturbance of the nature of an earthquake that shakes the ground 95 and would thus have a tendency to shake the building, the momentum of the building will be great enough to sink the shearing knives 14—14 further into the bars 16—16, and thus leave the building practically undisturbed. As the vertical movement in 100 earthquakes is very small and never amount to more than fractions of inches, these bars will be able to take care of such disturbances from several earthquakes. The bars 16 may be removed and replaced by new ones, through openings 10—10, if they become deeply sheared by repeated disturbances. The upper surface 5 of plate 1 and the lower surface of the bottom wall 7 of member 2, are smooth and said member therefore 110 may slide on the plate 1 if there is any hori-

zontal disturbance that would have a tendency to sway the building sideways.

The pin 20 has shearing strength enough to prevent wind pressures from moving the building off its foundations, but weak enough to shear if an earthquake or similar disturbance takes place, and thus leave the building comparatively undisturbed also from said motions.

10 After an earthquake or other disturbance, when the building has moved to one side and sheared the pin 20, a jack 25 may be placed under the sill 18 and the building raised thereby so that the knives 14-14 may be lifted out of the bars 16 and the building moved back to normal position with the apertures 6 and 9 in registration. The mutilated bars 16-16 and the sheared pin 20 may then be removed and others substituted and the building is ready to resist another earthquake.

While I have shown and described a specific embodiment of my invention I do not limit myself to the exact details of construction and arrangement shown, but may employ such changes and modifications as come within the scope of the appended claims.

Having described my invention, I claim—

1. In a device as disclosed, a plate provided with an aperture and placed within a building foundation, a socket base member placed on said plate and provided with openings in opposite side walls and with an aperture in its bottom wall adapted to register with the aperture in said plate, a pin inserted through said apertures having shearing strength enough to prevent wind pressures from moving the building but weak enough to shear if an earthquake or similar disturbance takes place, bars of soft material adapted to be introduced through said openings in said side walls into said base member, a supporting member telescopically mounted in said socket member, knives formed in said supporting member and resting in the upper edge of said bars, the sill of the building being mounted on said supporting member, the weight of the part of the building resting on said knife edges being just enough to sink into said soft metal bars but not enough to shear the same.

2. In a device as disclosed, a plate mounted in the building foundation, a socket base member slidably mounted on said plate, means for securing said socket base to said plate with sufficient strength to prevent wind pressures from moving the building, a supporting member telescopically mounted in said socket member, means within said socket base member upon which said supporting member rests, said means being able to take care of the vertical movements of the building caused by earthquakes, the building being mounted on said supporting member.

65 3. In a device as disclosed, a plate mounted

on the building foundation and provided with an aperture, a socket base member slidably mounted on said plate and provided with an aperture in the bottom wall thereof, a pin inserted through said aperture having shearing strength to prevent wind pressures from moving the building, but weak enough to shear if an earthquake or similar disturbance takes place, a supporting member for supporting the building telescopically mounted in said socket base, and means within said socket base member upon which said supporting member rests for taking care of the vertical movements of the building caused by earthquakes or other disturbance.

4. In a device as disclosed, a plate mounted in the building foundation, a socket base member slidably mounted on said plate, means for securing said socket base to said plate with sufficient strength to prevent wind pressures from moving the building but weak enough to permit the building to move sidewise by an earthquake or similar disturbance, said socket base having openings in opposite side walls, bars of soft metal adapted to be introduced through said openings into said socket base member, a building-supporting member telescopically mounted in said socket base member, knives formed on said supporting member resting in the upper edge of said bars, the weight of the part of the building resting on said knives being just enough to sink into said bars but not enough to shear the same.

5. In a device as disclosed, a plate mounted in the building foundation, a socket base member slidably mounted on said plate, means for securing said socket base to said plate with sufficient strength to prevent wind pressures from moving the building, a supporting member telescopically mounted in said socket member, upstanding longitudinal walls on said supporting member, upstanding transverse walls on said supporting member, the building still resting on said supporting member between said longitudinal walls and said sill having transverse grooves in the under side thereof in which said transverse walls rest, and means within said socket base member upon which said supporting member rests for taking care of the vertical movements caused by earthquakes or similar disturbances.

6. In a device as disclosed, a plate mounted in the building foundation, a socket base member slidably mounted on said plate, means for securing said socket base to said plate with sufficient strength to prevent wind pressures from moving the building but weak enough to permit the building to move sidewise by an earthquake or similar disturbance, bars of soft metal mounted in said socket base member, a building-supporting member telescopically mounted in said socket

base member, knives formed on said supporting member resting in the upper edge of said bars, the weight of the building resting on said knives being just enough to sink 5 said knives into said bars but not enough to shear the same

7 In a device of the character described, a foundation, a building, a support interposed between the building and the foundation 10 adapted to slide on the foundation, and means connecting the foundation and sup-

port opposing sliding movement of said support adapted to shear to permit sliding movement of the support under excessive strains.

15

8. A building support comprising a series of penetrable blocks, blades seating on said blocks and adapted to penetrate the same under excessive strain, means supporting said blocks, and means carrying said blades and 20 adapted to support a building.

OSCAR STROMBORG.
